UNITED STATES PATENT OFFICE.

JOHN ADAM FRENZEL, OF WAUSAU, WISCONSIN.

TRAIN-PIPE COUPLING.

No. 813,637.

Specification of Letters Patent.

Patented Feb. 27, 1906.

Application filed December 14, 1905. Serial No. 291,684.

To all whom it may concern:

Be it known that I, JOHN ADAM FRENZEL, a citizen of the United States, and a resident of Wausau, in the county of Marathon and State of Wisconsin, have invented certain new and useful Improvements in Train-Pipe Couplings; and I do hereby declare that the following is a full, clear, and exact description thereof.

10 My invention has for its object to provide simple, economical, automatic train - pipe couplings for railway-brakes; and it consists in certain peculiarities of construction and combination of parts hereinafter particularly 15 set forth with reference to the accompanying drawings and subsequently claimed.

Figure 1 of the drawings represents a central longitudinal section view of a train-pipe coupling in accordance with my invention 20 and fragments of coupled cars to which sections of said pipe - coupling are connected; Fig. 2, a partly-sectional view of the train-pipe coupling having the sections thereof disconnected; Fig. 3, a transverse section 25 view indicated by lines 3 3 in Fig. 1; and Fig. 4, a plan view of a portion of one of the coupling-sections, partly in section, on line 4 4 in said Fig. 1.

Referring by letter to the drawings, A indicates a rod supported in depending lugs b of draw-bar guides of a railway-car. The rod also engages upwardly-extending lugs c d of a hanger B, the rod-aperture in the forward lug c being vertically elongated to permit upward tilt of the hanger. The forward 35 end of the hanger is provided with an annular opening, transverse grooves e within the confines of the opening, and an annular flange f in rear of said opening. Bolted or otherwise 40 suitably secured to the front of the hanger or made integral therewith is a beveled collar g, that registers with the opening aforesaid and is provided with transverse inner grooves h in register with the ones above specified.

45 Loose in a depending rear arm i of the hanger is a section C of the train-pipe having a forward head D in screw - thread connection therewith. A spiral spring E is arranged under tension on said section of train-pipe 50 between the hanger-arm and pipe-head. In screw - thread union with the pipe - head is one end of a nozzle F, having a packing-gasket j, seated in a front recess thereof to protect therefrom, and the bore of the nozzle is 55 controlled by a check-valve k, guided therein, the rear portion of said bore being enlarged

to form a valve-chamber. The stem m of the valve is guided in a spider n in the nozzle-bore, and a spiral spring p is arranged under tension on said stem between a head q of 60 same and said spider. The nozzle is provided with diametrically opposite longitudinal recesses, and outer ribs r, parallel to the recesses, are extended in pairs forward of the remainder of said nozzle. Arranged in each 65 longitudinal recess of the nozzle and between a pair of ribs r of same is a lever G, the forward end of which has the form of a hook. A fulcrum - lug t of each lever engages a depression of the corresponding recess in the 70 nozzle, and a hook-lug u of the same lever has its play in another depression of said recess, this hook-lug being caught against a lip v of said nozzle to limit outward swing of the hook ends of said lever. Inward swing 75 of the hook end of the lever is limited by the flange y of the adjacent pipe-head D, that engages with the flange f of a hanger A when a nozzle F is in normal position.

The construction and relative arrangement 80 of parts above specified are duplicated in each section of my improved train - pipe coupling, the levers G, carried by the nozzle of one section, being at intervals of ninety degrees from those carried by the nozzle of the 85 other section of said coupling.

In practice when two cars, each properly equipped with a section of my improved train-pipe coupling, are brought together the heads q of the valve-stems p abut one another 90 to cause an unseating of the valves k against spring resistance, and the packing-gaskets j of the nozzles F, coming into contact one with the other, said nozzles are moved longitudinally against spring resistance to thereby 95 cause a tilt of the levers G in the direction necessary for the outer hook end w of each to catch over an opposing flange x of a nozzle, these outer hook ends of said levers being caught within the confines of the nozzle-collars q at about the time the coupling of the 100 cars is effected. The hangers B for the train-pipe-coupling sections being loose on their supporting-rods A, they are free to move longitudinally of said rods, as well as to swing 105 thereon and tilt, as aforesaid, according to various motions of the cars when the train is running. The cars being uncoupled and pulled apart, the nozzles of the train-pipe coupling automatically return to normal position, due to expansive force of the springs 110 E, and concurrent with this operation the le-

vers G are tilted to normal position as they are carried by the respective nozzles transversely of the front openings in the hangers and the adjacent collars. At the same time the springs p react to seat the valves k in the nozzles.

I claim—

1. The combination of a rod for suspension from a railway-car longitudinally of the same, a tilt-hanger in longitudinally-adjustable swing connection with the rod, a train-pipe section loose in an arm of the hanger and provided with a head, a spiral spring on the pipe-section under tension between the hanger-arm and pipe-head, a longitudinally-recessed nozzle extending from said pipe-head through a front opening in said hanger and provided with a forward packing-gasket surrounding its bore and projecting therefrom, a spring-controlled check-valve in the nozzle-bore having a stem provided with a head that normally projects beyond said nozzle, and grip-levers arranged in the nozzle-recesses to come in and out of engagement with a flange of a meeting nozzle similar to the one aforesaid.
2. The combination of a rod for suspension from a railway-car longitudinally of the same, a tilt-hanger in longitudinally-adjustable swing connection with the rod, a train-pipe section loose in an arm of the hanger and provided with a head, a spiral spring on the pipe-section under tension between the hanger-arm and pipe-head, a longitudinally-recessed nozzle extending from said pipe-head through a front opening in said hanger and provided with a forward packing-gasket surrounding its bore and projecting therefrom, a beveled collar on the front of the hanger in register with the opening of same, a spring-controlled check-valve in the nozzle-bore having a stem provided with a head that normally projects beyond said nozzle, and grip-levers arranged in the nozzle-recesses to come in and out of engagement with a flange of a meeting nozzle similar to the one aforesaid, the outer ends of the levers of one nozzle being caught within the confines of the beveled collar of the other nozzle.
3. The combination of a hanger depending from a railway-car, a train-pipe section loose in an arm of the hanger and provided with a head, a spiral spring on the pipe-section under tension between the hanger-arm and pipe-head, a longitudinally-recessed nozzle extending from said pipe-head through a front opening in said hanger and provided with a forward packing-gasket surrounding its bore and projecting therefrom, a spring-controlled check-valve in the nozzle-bore having a stem provided with a head that normally projects beyond said nozzle, and grip-levers arranged in the nozzle-recesses to come in and out of engagement with a flange of a meeting nozzle similar to the one aforesaid.
4. The combination of a hanger depending from a railway-car, a train-pipe section loose in an arm of the hanger and provided with a head, a spiral spring on the pipe-section under tension between the hanger-arm and pipe-head, a longitudinally-recessed nozzle extending from said pipe-head through a front opening in said hanger and provided with a forward packing-gasket surrounding its bore and projecting therefrom, a beveled collar on the front of the hanger in register with the opening of same, a spring-controlled check-valve in the nozzle-bore having a stem provided with a head that normally projects beyond said nozzle, and grip-levers arranged in the nozzle-recesses to come in and out of engagement with a flange of a meeting nozzle similar to the one aforesaid, the outer ends of the levers of one nozzle being caught within the confines of the beveled collar of the other nozzle.

In testimony that I claim the foregoing I have hereunto set my hand, at Wausau, in the county of Marathon and State of Wisconsin, in the presence of two witnesses.

JOHN ADAM FRENZEL.
